UNITED STATES PATENT OFFICE.

FRANCIS ELЛИCOTT, OF BALTIMORE, MARYLAND.

TURBINE WATER-WHEEL.

SPECIFICATION forming part of Letters Patent No. 664,391, dated December 25, 1900.

Original application filed September 13, 1899, Serial No. 730,383. Divided and this application filed January 17, 1900. Serial No. 1,789. (No model.)

To all whom it may concern:

Be it known that I, FRANCIS ELЛИCOTT, a citizen of the United States of America, and a resident of Baltimore city, in the State of Maryland, have invented certain new and useful Improvements in Turbine Water-Wheels, of which the following is a specification.

My invention relates to a turbine water-wheel and the peculiar construction of the buckets of the runner and the proportion of these buckets to the inlets; and the object of my invention is to secure high efficiency at any head and any quantity of water.

This application is a division of an application filed by me September 13, 1899, Serial No. 730,383.

In the drawings similar characters indicate the same parts in all figures.

Figure 1 is an external elevation of the wheel-casing, partially in section, showing inlets and runner. Fig. 2 is a vertical elevation of the runner removed from the casing. Fig. 3 is a rear view of one of the buckets. Fig. 4 is a front end view of one of the buckets. Fig. 5 is a section of one of the buckets through the line *x x* of Fig. 4. Fig. 6 is a section of the same bucket through the line *y y* of Fig. 4. Fig. 7 is a diagram showing the angle of curvature of the two parts of the bucket. Fig. 8 is a rear side view of the bucket. Fig. 9 is a front face view of the bucket, and Fig. 10 is a bottom view of the bucket.

Referring to Fig. 1, 1 is a case surrounding the runner and shaft.

2 2 are water-inlets through the walls of the casing, introduced at an angle so that the inner edge of each inlet shall be approximately tangent to the periphery of the runner—*i. e.*, to a circle described by the external edge of the buckets as they revolve. The outer wall of each inlet is tangent to a somewhat smaller circle.

3 is a cylindrical gate fitting closely into the wheel-casing and suitably connected to a mechanism by which it is raised and lowered to cover more or less of the mouths of the inlets, and thus admit a greater or less quantity of water to the runner. In the vertical side of the inlets 2 2 are grooves 4 4, opposite each other, and in practice I generally employ several sets of these grooves, which are on the same plane, at right angles to the axis of the

runner in all inlets. In these grooves are inserted a series of removable plates 5 5 5, the plates being of the same shape as the top and bottoms, but a little wider, so as to take into the grooves 4 4 and to divide each inlet into two or more parallel smaller inlets.

Fig. 1 shows the inlets with two sets of grooves and plates by which the inlets are divided into three sections. I have found that a higher efficiency can be secured with the same runner when the water entering the wheel through the inlets is divided and confined on the exterior of the gate than when it is not so confined. If the gate be opened one-third of the height of the inlet and no dividing-plate be used, the eddy currents on the exterior of the gate will to some extent destroy the efficiency of the water passing through that part of the inlet which is left open by the gate. If the open area of the inlet is circumscribed by the introduction of a dividing-plate and the entering water be given more positive direction by the rigid walls of the inlet, which converge directly to the mouth of the portion of the inlet which is open, the impact of the water upon the runner will be more effective and a greater amount of power will be developed. Hence while the water is low and the wheel is running at about one-third gate a higher efficiency can be obtained by the introduction of the dividing-plate such as is shown in this figure. The same is true when the wheel is running with the gate two-thirds open and a second plate is used. If the wheel be constructed to use the average water at full gate, the best results are accomplished by locating the grooves in positions corresponding to the proportioned decline of the supply, and then shifting the plates from one position to another as the supply fluctuates. The plates, therefore, are made removable, so that one set of plates may be used for the wheel, and they may be removed from one position to another as the quantity of water available for the purpose of the wheel varies, and this may be done with ease and facility, besides which the presence of a plate in the center of the inlet decreases the area and also acts to catch leaves or other solid matter in the water, and thus obstruct the inlet. The grooved inlets and removable plates

herein described have been made the subject of another application filed by me May 9, 1898, Serial No. 680,142.

6 is a toe mounted on a cross-bar at the 5 lower end of the casing. 7 is a socket fitting upon it.

8 is a main driving-shaft having a flange 9.

10 is a conical hub keyed upon the main driving-shaft 8 and resting upon the flange 10. The hub is conical in form on its exterior and curved inward, as shown in Fig. 2. To the surface of the hub 10 is secured a series of buckets 11 11 11 in the relative positions shown in Fig. 2. The bucket itself is shown 15 in detail in Figs. 3 to 10. The position shown in Fig. 4, which is a front end view, is the same as the view of the bucket at the center of the runner as it appears in Fig. 2. The bucket has a straight front edge which is 20 parallel to the axis of the runner and parallel to the interior of the cylindrical gate. It is sheared on its front edge, as shown in Figs. 5 and 6, so as to present a sharp edge and the least possible resistance to the water entering the inlet when the bucket is opposite the inlet. The upper portion of the bottom of the bucket—that is to say, of the portion with which the water entering the inlet makes contact when the gate is first opened by lowering—is convex. The convex surface referred to is marked 12 in Figs. 4 and 9. It will also be noticed that the area of the bucket at that point is small and it gradually enlarges toward the lower end of the bucket. The portion 30 of the bottom of the bucket marked 13 in Fig. 4 is concave, and there the area is much larger than at the point 12. The extreme end of the bucket is bent away from the direction of travel of the runner, and 40 the end of the bucket is curved almost at a right angle to form an outlet between the curved end and the back of the next following bucket.

Referring to the diagram Fig. 7, lines *a b* and *c d* intersect one another at *e* and are each tangent to the circle *g*. *f* is a circle having the same center as *g* and a radius equal to that of the runner, while *g* is a circle of calculated radius to which the lines *a b* and 50 *c d* are tangent. The radius of *g* is such as to give to *a b* and *c d* the desired angle at *e*. *a b* will represent the inclination of the upper portion of the bottom of the bucket, as shown in section in Fig. 5, and *c d* will represent the inclination of the portion of the 55 bottom of the bucket shown in Fig. 6. The area of the bucket from top to bottom is made to increase in a somewhat greater ratio than the area of the inlet—that is to say, the portion of the bottom of the bucket opposite a corresponding portion of the inlet above a horizontal plane is greater than the area of the inlet—and this area increases in a constantly-increasing ratio until the maximum 60 area of the bottom of the bucket is reached.

In the diagram Fig. 7, *a b* represent the inclination of the convex surface, and it will

will be perceived that the line *a b* makes, with a tangent to the circle *f* at *e*, an acute angle, which will cause the water to flow toward the angle and the edge of the bucket. The conical form of the hub serves at this point to contract the bucket, so as to form a pocket somewhat proportional in size to the amount of water being admitted. The downward incline of the bottom below allows a free escape for the water after it has expended its initial force in impact. The lower portion of the bucket 13 is concave and of much larger area than the upper part, required by 80 the fact that as the gate opens the quantity of water admitted increases and must be provided for.

The differences of angle upon which the bottom of the bucket is constructed, as shown in diagram Fig. 7, have been found to be important in order that the maximum efficiency of a small quantity of water may be secured when the gate is open only about one-third, in consequence of the water being low. A 90 maximum efficiency is secured by directing the impact of the inlet-jet at the extreme edge of the bucket. The angle of that portion of the bucket which the water strikes when the gate is nearly closed is therefore 95 made an acute angle with the tangent to the circle at the outlet, and the water is therefore thrown toward the periphery of the runner and the edge of the bucket, and the full leverage of the radius of the runner is employed. As the inlet is enlarged the quantity of water entering is too great to be utilized in the contracted portion of the bucket, and it is necessary, therefore, to give the bucket a greater area and also to give discharge direction to the current. This is accomplished by providing the lower part of the bucket with the pocket 13, the curve of which continues to the discharge end of the bucket. As the water enters the upper part of the inlet it will 100 strike upon the concave hub and be deflected downward and outward, and it is desirable to interpose into the path of this current a resisting-surface. Hence the angle of the bottom of the bucket is changed from the 105 position shown by the lines *a b* to the position shown by the lines *c d*, and the impact of the current as it is deflected from the conical hub outward against the bottom of the bucket will be availed of to rotate the runner. 110 This action produces an expenditure of the power of the water in impact and reaction at the greatest distance from the axis of the runner, and thereby produces the highest efficiency in rotation. The lower ends of the 115 buckets are turned in a direction almost at right angles to the edge. If they were extended to a complete right angle, the highest efficiency would result if other elements were 120 in proper relation; but I have found that a certain law must be obeyed in construction to secure the highest efficiency. Each bucket 125 being turned at a right angle and curved at its lower end when they are placed on the

conical hub, there will be a certain area between the bottom of one bucket and the back of the next—that is, the area of the discharge-opening out of which the water has to flow when escaping from the runner must be maintained at a certain relation to the area of inlet in order to get the best result. If the area of outlet be less than the area of inlet, the inlet-water will be retarded and the efficiency of the wheel will be lowered.

I have found by calculation and experiment that the highest efficiency is secured when the lower ends of the buckets are turned almost to a right angle and the area of the outlet is somewhat greater than the area of inlet. If the wheel be constructed with this relation of area of outlet to inlet at full gate, a lower efficiency will be secured at less than full gate. The efficiency may be raised, however, by readjusting the dividing-plates of the inlet, so as to make the inlet a complete one, having parallel top and bottom for the amount of water available for the wheel, and when the water is constant by removing one set of buckets and replacing them by another set the outlets of which bear the best relation to the inlets. As the area of outlet is increased in proportion to inlet the amount of water which will pass through the wheel, and consequently the horse-power of the wheel under constant head, will be increased; but the efficiency will be lowered. By reducing the diameter of the hub at the lower end to the diameter of the shaft and widening the buckets correspondingly I can increase the area of outlet, which will permit a corresponding increase of inlet, and thus accomplish a maximum water capacity and maximum horse-power for a given-sized wheel. My form of bucket, therefore, may be stated as being one the exterior edge of which is parallel to the axis of the runner and to the cylindrical gate. The bottom is convex at the upper portion or inclined at an acute angle with the tangent to the circle described by the end of the bucket at the point of the edge of the bucket. It is concave at the lower portion, or the bottom may be located at an obtuse angle to the tangent to the circle described by the edge of the bucket, and the bottom is bent at the lower end in an opposite direction to the motion of the runner and trough-shaped at its lower end, the interior of the edge of the bucket fitting a concave conical hub, which results in the bucket being widest at the bottom and gradually decreasing in area to the top. In practice the buckets are made with flanges and screwed onto the surface of the conical hub; but they may be attached to the hub in any way, so long as the shape is retained.

Referring to Fig. 9, 14 is a trough-shaped opening or bottom end of the bucket. 15 is the vertical straight edge, and 16 is the lower end, turned in the direction away from the motion of the runner.

Having described my invention, what I claim, and desire to secure by Letters Patent, is—

1. In a turbine water-wheel, the combination of a casing having water-inlets, a gate and a runner, the runner being provided with a series of buckets, having their outer edges practically straight and parallel to the axis of the runner, the upper portions of their bottoms being convex, the lower portion concave, and their lower concave ends turned in a direction opposite to the motion of the runner, substantially as described. 70

2. In a turbine water-wheel, the combination of a casing having water-inlets, a cylinder gate and runner, the runner being formed with a concave conical hub and a series of buckets attached to the exterior surface of the hub, the outer edges of the bucket being practically straight and parallel to the axis of the runner, the upper portion of their bottoms being convex, the lower portions being concave, and their lower concave ends being turned in a direction opposite the motion of 85 the runner. 90

3. In a turbine water-wheel, the combination of a casing having water-inlets, a gate and a runner, the runner being provided with a series of buckets having their outer edges practically straight and parallel to the axis of the runner, the upper portions of the bottoms of the buckets being convex, the lower portions concave, and the lower concave end turned in a direction almost a right angle opposite to the direction of the motion of the runner, and having an outlet area slightly greater than the inlet area, as and for the purpose specified. 95

4. In a turbine water-wheel the combination of a casing having water-inlets, a gate, and a runner, the runner being provided with a series of buckets having their outer edges practically straight and parallel to the axis of the runner and their bottoms convex at the upper part and concave at the lower part, these parts being oppositely inclined to a radial plane of the wheel, substantially as described. 105

5. In a turbine water-wheel the combination of a casing and a water-inlet, a descending cylindrical gate, and a runner, the runner being provided with a series of buckets having their outer edges practically straight and parallel to the axis of the runner, the upper portions of their bottoms being convex, the lower portions concave, these portions being oppositely inclined to a radial plane of the wheel and having their lower concave end turned in a direction opposite to the motion 110 of the runner, substantially as described. 115

Signed by me at Baltimore city, State of Maryland, this 12th day of January, 1900.

FRANCIS ELLICOTT.
